WIRE SUPPORT BRACKET FOR UTILITY POLES

Eugene R. Glazier, 2565 S. University Blvd.,
Denver, Colo. 80210

Filed June 15, 1966, Ser. No. 2,682

Term of patent 14 years

(Cl. D26—9)

FIG. 1 is a front elevational view of a wire support bracket for utility poles embodying my new design;

FIG. 2 is a side elevational view of the wire support bracket;

FIG. 3 is a rear elevational view of the wire support bracket;

FIG. 4 is a top plan view of the wire support bracket; and

FIG. 5 is a bottom plan view of the wire support bracket.

I claim:

The ornamental design for a wire support bracket for utility poles, substantially as shown.
